CARL Z. ALEXANDER, OF WEST LIVINGSTON, AND EARL S. ALEXANDER, OF NEWARK, NEW JERSEY, ASSIGNEES, BY MESNE ASSIGNMENTS, TO EDWIN C. SEWARD, OF JERSEY CITY, NEW JERSEY.

STEAM-BOILER ATTACHMENT.

Application filed January 18, 1922. Serial No. 530,196.

This invention relates especially to steam heating or other boilers in which special geyser devices are arranged to automatically supply water to the upper sections or portions of the boiler in which this water is preferably evaporated in thin sheets or streams. Many of the sectional steam heating boilers are provided with transverse evaporating channels or heating surfaces which when the lower surfaces of these channels are slightly inclined and preferably somewhat ribbed or corrugated form efficient evaporating surfaces when water is automatically supplied thereto during the operation of the boiler by geyser devices of the general type covered by the Alexander Patent 1,240,804 of September 25, 1917. These geyser devices may in many cases comprise one or more coils of pipe or other evaporating units installed in the fire box portion or section of the boiler and having a water supply pipe and geyser tube or discharge connection which may be conveniently carried out in many cases through the usual cored holes which are cast in heating boilers for hot water connections. In this way when the boiler is operating sufficient evaporation occurs in these geyser devices to automatically supply water to the upper sections of the boiler where it may be distributed over the evaporating channels or heating surfaces to be evaporated thereon efficiently and supplement the steam generated in the lower part of the boiler, the water line being, of course, kept substantially lower than in regular boiler practice so that at least a considerable proportion of the upper heating surfaces can act as steam chambers or channels in which this film type evaporation can take place as in the Alexander boilers.

In the accompanying drawing, showing various illustrative embodiments of this invention,

Fig. 1 is a vertical side section taken through a substantially square bodied or sectioned boiler, on line 1—1, Fig. 2.

Fig. 2 is a vertical rear sectional view thereof on line 2—2, Fig. 1, looking toward the front.

Fig. 3 is a vertical side section through another type of boiler.

Fig. 4 is a partial front vertical section thereof.

Fig. 5 is a partial side section through another illustrative boiler, and

Fig. 6 is a front vertical section thereof.

The boiler may be of any desired type and construction and preferably comprises a number of evaporating channels or heating units which may be operated above the normal or static water level in the boiler so as to evaporate under efficient conditions the films or streams of water supplied thereto by the connected geyser devices. In the Fig. 1 arrangement the ashpit portion 1 may be provided with the usual door 2 and with a grate on which may rest the fire 3 in the fire box portion 4 of the boiler which may be of water jacketed construction so as to have the water space 5. This fire box section may have connected thereto by push nipples or otherwise the desired number of superimposed evaporating sections such as 7, 10 and 11 on which a steam dome such as 21 may be mounted and provided with smoke passages 22, 23 to which the smoke pipe may be connected. Each of these evaporating sections may, as indicated in Fig. 2, comprise a series of separated channels such as 7 which preferably have their upper surfaces somewhat arched or inclined to facilitate the discharge of soot from these reduced area upper surfaces while the lower heating surfaces of each of these channels is flatter and preferably somewhat inclined as from the front to the rear of the boiler and in the upper evaporating sections at least this lower surface such as 8, 9 is preferably ribbed or corrugated so as to form water diffusing or spreading channels to facilitate the water diffusion and evaporation therefrom. These sections may be connected in any suitable way as by the desired number of push nipples 12, 13, 14 and 15 between the adjacent sections so as to allow ample circulation of water and steam between them while allowing for the heat expansion which takes place between the sections under service conditions. As indicated in Fig. 1, several of the upper rows or sets of evaporating channels are above the normal or static water line 6 which is preferably, though not necessarily, run high enough so as to keep the lower row of evaporating channels next the fire normally covered with water.

The geyser device may be of any suitable

type and construction and may, for example, as indicated in Fig. 2, comprise one or more geyser pipes or coils 25 arranged within the fire box section of the boiler so as to be within or adjacent the fire and be effectively heated when the boiler is in operation. These geyser devices preferably have a water supply connection such as 26 to a water space in the boiler so that water is supplied to one end of each of these pipes or devices in which sufficient evaporation takes place under operating conditions to carry up considerable amounts of water with the steam generated in the upper part of the boiler for distribution over the upper heating surfaces thereof. For this purpose each geyser device may have a geyser tube or connection 24 extending upward to supply the water to the different evaporating channels or portions and for some purposes one or more feed boxes or devices such as 16 may be used to equalize to the desired extent the feed of water to the evaporating channels on the different levels in the boiler. The water from one of these geyser tubes 24 may be delivered into the feed box 16 in which a row of feed pipes such as 17', 20' may be arranged on substantially the same level at the lower part of the feed box so that, if desired, substantially equal proportions of this water may be delivered to each of the distributing pipes 17, 20 extending across the row of evaporating channels for instance and having one or more distributing tubes 18, 19 extending into each distributing channel. By making the size or inlet opening of the feed pipe 20' somewhat smaller to compensate for its greater effective head equal amounts of water may be supplied to each level or set of evaporating channels fed in this way although in many cases it is desirable to feed rather more water to the lower evaporating channels which are more highly heated because nearer to the fire. Each distributing tube 19 preferably extends into the main channel 10 so that the water therefrom is delivered upon the corrugated or other inclined lower surface 8 down which it runs or flows in thin sheets or streams to be evaporated under highly efficient conditions before the surplus water passes through the nipple connection such as 14 to the lower parts of the boiler. This arrangement has, of course, decided advantages since it makes it possible to use such efficient geyser operation with this type of steam boiler which may in some cases, of course, be operated without the geyser devices by merely carrying the water line up to or beyond the upper evaporating channels 11 extending across the boiler.

Figs. 3 and 4 show another type of sectional boiler comprising the ashpit portion 28 and fire box portion 29 which may have the water space 30 therein, the grate 44 of

any suitable construction being arranged at the bottom of this fire box section. The normal water line 31 may be carried in this case slightly above the lower water leg or section 33 so that at least its lower heating surface 32 is kept substantially covered and, if desired, the water line 31 may be carried considerably higher as is indicated in Fig. 3. The upper heating units or portions extending more or less across the heating space in the boiler may comprise somewhat inclined heating units or portions 35, 36 connected together and to the steam dome 38 by suitable screw or push nipple connections as is usual in this art. The smoke spaces are arranged between these different heating units so as to effectively heat them from the hot gases which are finally conducted out through the smoke chamber 40 and smoke pipe connection 41 to be led to the chimney. The geyser device may be of any suitable construction and as indicated in Fig. 4 it may comprise a single sinuous or zigzag coil or pipe 45 having the water supply connection 46 communicating with the water jacket or other water space of the boiler while the geyser tube or connection 47 may lead to a feed box or device 48 of any suitable construction to supply water under running conditions to the different distributing pipes 42 and connected distributing tubes 43 leading into the evaporating chambers or units at different portions thereof as is indicated in Fig. 4. Thus the upper heating surfaces may operate as steam chambers to evaporate the water passing over them in thin sheets or films, the steam being carried up into the steam dome having the steam supply connection 39. Another arrangement shown in Figs. 5 and 6 may comprise the ashpit portion 441 and connected fire box portion 451 having the water space 461 communicating with one or more transverse water spaces or evaporating portions 67. The upper evaporating portions or sections 57, 64 may be connected to the fire box section through suitable push nipple or other connections 52, 53, 54 and the smoke passages such as 51, 511, allow the hot gases to circulate through and around the upper heating units so that these hot gases pass from the spaces 481, 49, 50 into the smoke passage 56 to which the breaching or smoke pipe connection 55 is united. An illustrative geyser device is shown in this case as comprising the sinuous coil 59 in the fire box having the supply connection 65 connected with the fire box water jacket and having at its other end the geyser tube or connection 60, 61 leading to a distributing device or box 62. In this way any desired number of distributing pipes or tubes 63 may be led into the different parts of the upper evaporating sections or chambers so that the water under operating conditions of the boiler is amply

distributed over these heating surfaces above the normal water level 471 and flows over them as it is evaporated efficiently in the form of thin films or streams.

5. This invention has been described in connection with a number of illustrative embodiments, forms, proportions, parts, arrangements, materials, constructions and methods of manufacture and use, to the details of which disclosure this invention is not of course to be limited, since what is claimed as new and what is desired to be secured by Letter Patent is set forth in the appended claims:

15. 1. A steam heater comprising a fire-box section and a plurality of evaporating chambers above the water level and through which water is adapted to flow in thin sheets, and a geyser device having a heating portion within said fire-box section in communication with the water space thereof and distributing connections extending one to each of said evaporating chambers to automatically supply water to all of them simultaneously.

20. 2. A steam heater comprising a fire-box section and a plurality of superimposed evaporating sections above the water level through which water is adapted to flow in thin sheets, and a geyser device having a heating portion within said fire-box section in communication with the water space thereof and distributing connections extending one to each of said evaporating sections to automatically supply water to all of them simultaneously.

35. 3. A steam heater comprising a fire-box section and an upper section having a number of evaporating channels above the water level and through which water is adapted to flow in thin sheets, and a geyser device leading from the said fire-box section and having a series of distributing connections extending one to each of said channels to automatically supply water to them simultaneously.

40. 4. A steam heater comprising a fire-box section and a plurality of evaporating chambers above the water level and through which water is adapted to flow in thin sheets, and a geyser device having a heating portion within said fire-box section in communication with the water space thereof a geyser tube leading from said heating portion and distributing connections extending one to each of said evaporating chambers to automatically supply water to all of them simultaneously.

45. 5. A steam heater having a fire-box section and an evaporating section above the water level, a feed box higher than said evaporating section, a geyser device leading from the said fire-box section to said feed box, and a connection from said feed box to said evaporating section.

6. A steam heater comprising a fire-box section, and a plurality of evaporating chambers above the water level and through which water is adapted to flow in thin sheets, a feed box higher than said evaporating chambers, a geyser device leading from the said fire-box section to said feed box, and distributing connections from said feed box one to each of said evaporating chambers.

7. A steam heater comprising a fire-box section and an upper section having a number of evaporating channels above the water level and through which water is adapted to flow in thin sheets, a feed box higher than said evaporating channels, a geyser device leading from the fire-box section to said feed box, and distributing connections from said feed box one to each of said evaporating channels.

8. A steam heater comprising a fire-box section and an upper section having a number of evaporating channels above the water level and through which water is adapted to flow in thin sheets, feed boxes higher than said evaporating channels, geyser devices leading from the fire-box section one to each of said feed boxes, a distributing pipe extending between said feed boxes, and tubes leading from said pipe one into each of said evaporating channels.

9. A boiler comprising a fire box section and a superimposed series of evaporating sections each comprising a number of inclined evaporating channels having relatively flat corrugated lower surfaces over which water is adapted to flow in thin sheets or streams, a geyser device arranged within the fire box section of the boiler and communicating with a water space, a feed box detachably mounted outside the boiler and connected with said geyser device and having a series of substantially level feed pipes communicating with distributing pipes and tubes extending into each of the evaporating channels in the different sections of the boiler above the normal water line to automatically supply water thereto.

10. A boiler comprising a fire box section and a superimposed series of evaporating channels having lower surfaces over which water is adapted to flow in thin sheets or streams, a geyser device arranged within the fire box section of the boiler and communicating with a water space, a feed box detachably mounted outside the boiler and connected with said geyser device and having a series of substantially level feed pipes communicating with distributing pipes and tubes extending into the evaporating channels above the normal water line to automatically supply water thereto.

11. A boiler comprising a number of evaporating portions above the water level and in which water is adapted to flow in thin sheets, a geyser device communicating

with a water space of the boiler, a feed device connected with said geyser device and having a series of substantially level feed pipes communicating with distributing tubes one for supplying water to each of the said evaporating portions of the boiler above the water line.

12. The geyser device attachment for sectional steam boilers which have a series of superimposed evaporating sections, comprising a geyser coil device adapted to be mounted in the fire box section of the boiler and supplied with water under operating conditions, a connected geyser tube and feed box and a series of feed pipes extending into said feed box and connected distributing pipes and tubes adapted to extend into each evaporating unit in the upper evaporating sections of said boiler to automatically sup-

ply water to said evaporating units above 20 the normal water line of the boiler under operating conditions.

13. The geyser device attachment for sectional steam boilers which have a series of superimposed evaporating sections, comprising a geyser device adapted to be mounted 25 in the boiler and supplied with water under operating conditions, a connected geyser tube and feed box and a series of feed pipes extending 30 into said feed box and connected distributing pipes adapted to extend into each evaporating unit in the upper evaporating sections of said boiler to automatically supply 35 water to said evaporating units above the normal water line of the boiler under operating conditions.
